UNITED STATES PATENT OFFICE.

PAUL SCHOLL, OF BERLIN, GERMANY, ASSIGNOR TO ERNST AHLERT, OF SOUTH PASADENA, CALIFORNIA.

SAFETY DEVICE FOR LOCKS.

1,379,048.

Specification of Letters Patent.

Patented May 24, 1921.

Application filed November 10, 1920. Serial No. 423,178.

To all whom it may concern:

Be it known that I, PAUL SCHOLL, a citizen of Germany, residing at Berlin, Germany, have invented a new and useful Improvement in Safety Devices for Locks, of which the following is a specification.

The invention relates to door locks, and more particularly to a safety device for locks and doors of all kinds.

10 It is an object of the invention to provide a locking bolt adapted to engage the latch of a lock and releasable only by an extension of a key with which the lock is actuated.

15 It is a further object of the invention to provide on the inside of the door a plate which may be adjusted in position to prevent or permit the extension of the key to remove the locking bolt from engagement with the latch.

20 It is also an object of the invention to provide certain features of construction and arrangement whereby devices of the kind specified are rendered highly efficient and their desirability greatly enhanced.

25 To the accomplishment of the objects stated, and others that will become more apparent as the description of the invention proceeds, a preferred embodiment of the invention is described in the following specification and particularly pointed out in the claims forming a part thereof.

30 The annexed drawing discloses a preferred embodiment of the invention without, however, exhausting the possible modifications 35 which may be constructed on the principle on which the present invention is predicated.

In the drawing:

Figure 1 is a fragmentary view of the door provided with a lock and safety means 40 in accordance with the invention;

Fig. 2 is a section on the line 2-2 of Fig. 1;

Fig. 3 is a view similar to Fig. 2 with the key inserted and the safety means released; 45 and,

Fig. 4 discloses several enlarged shapes of the safety release.

Referring to the several views of the drawing, 1 designates a door which is equipped 50 with a keyhole 2 and with a lock including a latch 3 controlled by a spring impelled pawl 3'. The latch 3 is provided with a plurality of openings 4 for a purpose herein-after further referred to. The door 1 is

equipped with a circular aperture 5 originating at the inner side of the door and extending to the lock at right angles to the path of movement of the latch. A sleeve 6 is arranged in the aperture 5 and receives a bolt 7 which adjacent to its operative end is 60 equipped with a disk 8, whereby the bolt is guided within the sleeve 6. The bolt 6 is formed at its inner end with a knob 9, and interiorly of the sleeve a spring 10 bears against the disk 8 and against the end wall 65 of the sleeve 6, whereby the bolt is continuously forced toward the lock. The sleeve is secured to the door by a plurality of screws 12 threaded into the door and extending through the end plate. 70

From the foregoing, it is obvious that the bolt 7, under the influence of the spring 10, is forced into an opening 4 of the latch 2, so that manipulation of the latch by means of a key is not possible unless the locking or 75 safety bolt 7 is withdrawn from the latch. As indicated in the sectional views, the bolt 7 has pivotally secured thereto a depending plate 13 which is arranged on the inner side of the door and constitutes an engagement 80 means whereby the bolt 7 may be released from engagement with the latch 2 by an actuator introduced through the keyhole. This plate may, if desired, be manipulated to be swung laterally out of alignment with the 85 keyhole.

As indicated in Fig. 3, a key 14 has secured to its end a sleeve portion 15 which terminates in a solid pin 16 adapted to engage the plate 13 when the key is inserted 90 through the keyhole 2. If it be desired to prevent the release of the bolt from the latch, such as is the case during the night, to secure the lock, a plate 17 is slidably mounted on the inner face of the door rearwardly 95 of the plate 13 by means of a plurality of screws 18 which extend through slots 19 provided in the plate 17. In the position of plate 17, shown in Fig. 1, an aperture 20 of the plate is in alignment with the path which the pin 16 takes upon insertion of the key and extension into the keyhole. If, however, the plate 17 is shifted laterally toward the left, as viewed in Fig. 1, the aperture 20 will not be in alignment with the pin 16 so that upon insertion of the key the pin 16 meets an unperforated portion of the plate 17 and, therefore, cannot engage the plate 100 105

13 to effect withdrawal of the bolt and release of the latch.

The operation of the device is thought to be obvious from the foregoing description. 5 To manipulate the lock, the plate 17 is arranged to have its aperture 20 in registering position so that a key together with its extension upon introduction into the keyhole may pass through aperture 20 to force inwardly the depending plate 13 to withdraw the bolt 7 from the latch 3, whereupon the latch may be shifted in the ordinary manner to effect locking or unlocking of the door. If, however, actuation of the lock is to be 15 prevented, the access of the key extension to the depending plate 13 is prevented by laterally shifting the abutment plate 17, so that the extension 16 will meet with an unperforated part of the plate and will thereby be 20 prevented from engaging the depending plate 13. As an additional precaution the depending plate 13 may be swung laterally clear of the keyhole 2.

The plate 17, instead of being provided 25 with a circular aperture 20, may have irregular slots, two forms of which are shown in Fig. 4.

While the drawing discloses a preferred embodiment of the invention, it is not intended to limit the invention to the exact details of construction and arrangement, as shown, but all modifications, alterations and changes are included, constituting departures within the scope of the invention, as 35 indicated by the following claims:

I claim:

1. In combination with a door lock, having a perforated latch, a bolt extending from the inner side of the door and adapted to 40 enter an aperture in said latch, and means secured to the key for withdrawing the bolt from the latch and means for preventing access to said bolt by said key secured means.

2. In combination with a door lock, having a perforated latch, a bolt extending from the inner side of the door and adapted to enter an aperture in said latch, a plate depending from said bolt at the inner end thereof to cover the keyhole, and means secured to the key for engagement with said plate and withdrawal of said bolt and means for preventing access to said plate by said key secured means.

3. In combination with a door lock, having a perforated latch, a bolt extending from the inner side of the door and adapted to enter an aperture in said latch, a plate pivoted on said bolt at the inner end thereof to cover the keyhole, and means secured to

the key for engagement with said plate and withdrawal of said bolt.

4. In combination with a door lock, having a perforated latch, a bolt extending from the inner side of the door and adapted to enter an aperture in said latch, a plate pivoted on said bolt at the inner end thereof to cover the keyhole, and a detachable extension on the key for engagement with said plate and withdrawal of said bolt.

5. In combination with a door lock, having a perforated latch, a bolt extending from the inner side of the door and adapted to enter an aperture in said latch, a spring surrounding said bolt and engaging a shoulder thereon to force the same toward said latch, a plate pivoted on said bolt at the inner end thereof to cover the keyhole, and means secured to the key for engagement with said plate and withdrawal of said bolt.

6. In combination with a door lock having a perforated latch, a bolt extending from the inner side of the door and adapted to enter an aperture in said latch, a plate depending from said bolt at the inner end thereof to cover the keyhole, a shiftable plate secured to the door rearwardly of said depending plate and having an aperture, and means secured to the key adapted to project through the aperture of said shiftable plate for engagement with said depending plate and withdrawal of said bolt from said latch.

7. In combination with a door lock, having a perforated latch, a bolt extending from the inner side of the door and adapted to enter an aperture in said latch, a plate pivoted on said bolt at the inner end thereof to cover the keyhole, means secured to the key for engagement with said plate and withdrawal of said bolt from said latch, and means for respectively permitting and preventing access of said key-secured means to said depending plate.

8. In combination with a door lock, having a perforated latch, a spring-controlled bolt extending from the inner side of the door and adapted to enter an aperture in said latch, a plate pivoted on said bolt at the inner end thereof to cover the keyhole, a shiftable plate secured to the door rearwardly of said depending plate and having an aperture, and means secured to the key adapted to project through the aperture of said shiftable plate for engagement with said depending plate and withdrawal of said bolt from said latch.

In witness whereof I affix my signature.
PAUL SCHOLL.
